L. D. NELSON

AUTOMOBILE HEATER

Filed Nov. 17, 1923

Inventor
Lewis D. Nelson
Chappell & Earl

Attorneys

Patented Oct. 27, 1925.

UNITED STATES PATENT OFFICE.

LEWIS D. NELSON, OF COLDWATER, MICHIGAN.

AUTOMOBILE HEATER.

Application filed November 17, 1923. Serial No. 675,343.

To all whom it may concern:

Be it known that I, LEWIS D. NELSON, a citizen of the United States, residing at Coldwater, county of Branch, State of Michigan, have invented certain new and useful Improvements in Automobile Heaters, of which the following is a specification.

This invention relates to improvements in automobile heaters.

The main object of this invention is to provide an improved automobile heater which may be utilized in connection with a heater for the intake manifold and for heating air for the carburetor, which may be quickly applied without disassembling the parts of the automobile to which it is applied.

Further objects, and objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a side elevation of a structure embodying the features of my invention, the intake and exhaust manifolds and exhaust pipe of an internal combustion engine being indicated by dotted lines and a portion of the floorboard of the vehicle being shown in order to illustrate the relation of my improved heater to these parts when installed.

Fig. II is a plan view of the parts disassembled, the manifold housing being partially broken away.

Fig. III is an inverted view of the register box and conduit members, the register box being partially broken away.

In the drawing similar reference characters indicate similar parts in all of the views.

Referring to the drawing, 1 represents the footboard of a motor vehicle, 2 the intake manifold and 3 the exhaust manifold thereof. I provide a housing comprising a front side wall section 4 and a top wall section 5, the top wall section being detachably and adjustably secured by providing it with the slotted lugs 6 engaged by the screws 7. The side wall is extended at 8 rearwardly beyond the top wall as shown in Fig. II.

The section 4 is provided with a nipple 9

at its rear end adapted to receive the pipe 10 connected to the air inlet of the carburetor, the carburetor not being shown.

The register box 11 has an opening 12 on its under side adapted to engage the exhaust pipe shown by dotted lines at 13, that is, the register box may be engaged with the pipe by a lateral movement relative thereto. The register face 14 is detachably secured to the register box by means of screws 15 engaging the ears 16 on the box. This register box is adapted to be set into the floorboard 1 as shown in Fig. I.

The conduit member 17 has telescoping engagement with the front end of the register box and is secured thereto by means of the rivets 18, the rivets being disposed at the upper sides of these members permitting telescoping adjustment between the register box and the conduit member. The conduit member is open on its under side so that it may be placed at the rear end of the exhaust manifold, it having a rear wall 19 depending at the rear of the manifold and a top wall 20 complementing the top wall 5 of the housing.

The conduit member has a slot 21 registering with the bolt-hole 22 in the ear 23 on the housing member so that the bolt or screw 24 may be readily engaged with the ear and a limited adjustment between the parts permitted to compensate for structural inaccuracies and variations in relation of the floorboard to other parts.

This arrangement of parts enables their being quickly and easily assembled in an automobile by persons not skilled. The parts also have the advantage of being very economical in structure.

Having thus described my invention what I claim as new and desire to secure by Letters Patent is:

1. In a structure of the class described, the combination of a housing for the exhaust manifold of an internal combustion engine comprising a top wall and a side wall, the side wall being extended rearwardly beyond the top wall and provided with an inwardly projecting lug having a bolt opening therein, a register box adapted to be inserted in the footboard of a motor vehicle and having an opening in the bottom wall thereof adapted to fit over the exhaust pipe of an internal combustion engine, a conduit member having telescoping engagement with the front end of said register box, connecting rivets

- for said conduit member and register box disposed at the top thereof permitting relative tilting adjustment of the parts, said conduit being adapted to overlap the rear end of said side wall and complement said housing top and having a slot therein registering with said bolt hole in said lug, and a bolt disposed through said slot to engage said lug.
10. 2. In a structure of the class described, the combination of a housing for the exhaust manifold of an internal combustion engine comprising a top wall and a side wall, the side wall being extended rearwardly beyond the top wall, a conduit member adapted to overlap the rear end of said housing side wall and complement the said housing top wall, means for adjustably securing said conduit member to said housing, a register box adapted to be inserted in the footboard of a motor vehicle, and connecting pivots for said register box to said conduit member disposed to permit the tilting adjustment of the register box relative to the conduit member.
15. 3. In a structure of the class described, the combination of a housing for the exhaust manifold of an internal combustion engine, a register box adapted to be inserted in the footboard of a motor vehicle and having an opening in the bottom wall thereof adapted to fit over the exhaust pipe of an internal combustion engine, a conduit member having telescoping engagement with the front end of said register box, connecting rivets for said conduit member and register box disposed at the top of the register box permitting relative tilting adjustment of the parts, and said conduit being adapted to overlap the rear end of said side wall and complement said housing top.
20. 4. In a structure of the class described, the combination of a housing for the exhaust manifold of an internal combustion engine, a register box adapted to be inserted in the footboard of a motor vehicle and having a slot-like opening in the bottom thereof adapted to receive the exhaust pipe of an internal combustion engine when presented laterally thereto, and a conduit member connecting said housing and register box, said register box being pivotally associated with said conduit member to permit tilting adjustment of the register box.
25. 5. In a structure of the class described, the combination of a housing for the exhaust manifold of an internal combustion engine, a register box adapted to be inserted in the footboard of a motor vehicle and having an opening in the bottom thereof adapted to receive the exhaust pipe of an internal combustion engine when presented laterally thereto, and a conduit member connecting said housing and register box, said register box being pivotally associated with said conduit member to permit tilting adjustment of the register box.
30. 6. In a structure of the class described, the combination of a housing for the exhaust manifold of an internal combustion engine, a register box adapted to be inserted in the footboard of a motor vehicle and having an opening in the bottom thereof adapted to receive the exhaust pipe of an internal combustion engine when presented laterally thereto, and a conduit member connecting said housing and register box, said register box being pivotally associated with said conduit member to permit tilting adjustment of the register box.
35. 7. In a structure of the class described, the combination of a housing for the exhaust manifold of an internal combustion engine, a register box adapted to be inserted in the footboard of a motor vehicle and having an opening in the bottom thereof adapted to receive the exhaust pipe of an internal combustion engine when presented laterally thereto, and a conduit member connecting said housing and register box, said register box being pivotally associated with said conduit member to permit tilting adjustment of the register box.

In witness whereof, I have hereunto set my hand.

LEWIS D. NELSON.
